(57) **CLAIM**

The ornamental design for a counter light fixture, as shown and described.

DESCRIPTION

FIG. 1 is a front top perspective view of the counter light fixture showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a bottom, front perspective view of the counter light fixture showing a second embodiment of my new design with the only difference from the first embodiment being a transparent panel to show the fluorescent tube arrangement therein;

FIG. 9 is a bottom, front perspective view thereof showing the transparent panel in the open position;

FIG. 10 is a bottom, front perspective view of the counter light fixture showing a third embodiment of my new design with the only difference from the second embodiment being a two-lamp light source; and,

FIG. 11 is a bottom, front perspective view thereof showing the transparent panel in the open position.
